(57) **CLAIM**

The ornamental design for an active wall plate, as shown and described.

DESCRIPTION

FIG. 1 is a front view of an active wall plate in accordance with our new design;

FIG. 2 is a top view thereof;

FIG. 3 is a bottom view thereof;

FIG. 4 is a left side view thereof;

FIG. 5 is a right side view thereof;

FIG. 6 is a perspective view thereof;

FIG. 7 is a front view of another active wall plate in accordance with our new design;

FIG. 8 is a top view thereof;

FIG. 9 is a bottom view thereof;

FIG. 10 is a left side view thereof;

FIG. 11 is a right side view thereof;

FIG. 12 is a perspective view thereof;

FIG. 13 is a front view of another active wall plate in accordance with our new design;

FIG. 14 is a top view thereof;

FIG. 15 is a bottom view thereof;

FIG. 16 is a left side view thereof;

FIG. 17 is a right side view hereof; and,

FIG. 18 is a perspective view thereof.

The broken lines represent portions of the active wall plate that form no part of the claimed design.
